UNITED STATES PATENT OFFICE.

ALLEN B. NORTON, OF CLEVELAND, OHIO, ASSIGNOR TO ALUMINUM COMPANY OF AMERICA, OF PITTSBURGH, PENNSYLVANIA, A CORPORATION OF PENNSYLVANIA.

METAL MOLD.

Original application filed May 25, 1923, Serial No. 641,359. Divided and this application filed March 16, 1925, Serial No. 15,796. Renewed April 5, 1928.

This invention relates to metal molds for casting light weight metals having a high crystallization shrinkage, as compared with iron. In particular, it is concerned with a 5 mold for casting thin walled articles composed of aluminum or its alloys.

Heretofore it has been found difficult to cast successfully articles composed of aluminum or aluminum alloys of the dimensions 10 most desirable in articles such as cooking utensils. Such articles are of various sizes and shapes but nearly all have relatively thin walls or wall portions which are not easily cast of the metals described in permanent 15 molds of the present types with which I am familiar.

Another difficulty experienced in casting such articles is that when the articles are cast on their sides or edges, their vertical 20 dimensions are so great that the molten metal must travel a considerable vertical distance from the top of the mold to the bottom of the casting cavity, which distance, in many instances, is sufficient to cause agitation or breaking up of the molten metal as 25 it enters the casting cavity and the formation of pores, pits and other imperfections in the surface of the casting which renders attainment of a polished surface free from blemishes difficult or impossible.

I have found however that articles of the class described having smooth substantially unpitted surfaces may be cast successfully 30 of aluminum or aluminum alloys in permanent molds and with walls or wall portions much thinner than has previously been possible by suitably shaping and positioning a gate with respect to the casting cavity, so 35 that the entering molten metal need flow only a minimum distance through the shallow 40 portions of the casting cavity in which the thin wall portions of the article are cast. Furthermore I have found that by use of a new and improved form of gate, I can cast 45 articles of the class described having relatively large vertical dimensions substantially without any of the present disadvantages which have been partially enumerated above.

One object of my invention is to provide a 50 new and improved gate for conducting molten, light weight metal, under the action of gravity, into a casting cavity from a con-

siderable height in a manner to prevent leaping or splashing of the metal or other agitation thereof sufficient to result in entrapping 55 air in the metal and to cause porosity or surface pitting of the casting; to avoid heating certain parts of the mold excessively; and to separate light weight, floating impurities from the molten metal before the metal enters the casting cavity.

Another object is to provide a new and improved gate for conducting molten, light alloy metal into a vertically elongated casting cavity from a point well above the upper 60 extremity of the cavity substantially without harmful agitation.

Another object is to provide a new and improved arrangement of gate and feeder 65 cavities with respect to a casting cavity for 70 articles having thin wall sections whereby the entering molten metal is caused to flow a minimum distance through the shallow portions of the casting cavity.

Other objects will appear and be pointed 75 out hereinafter.

In the drawings attached hereto and forming a part of this specification:

Fig. 1 is a top plan view of one form of mold constructed in accordance with my in- 80 vention.

Fig. 2 is an elevation partly in cross section taken on line 3—3 of Fig. 1 showing a casting in the casting cavity.

Figs. 3, 4, 5, 6 and 7 are fragmentary, 85 horizontal cross sections taken on lines 3—3, 4—4, 5—5, 6—6 and 7—7 of Fig. 2 showing relative sizes of various parts of the gate and feeder cavities.

Fig. 8 shows in perspective a casting as 90 made in the improved mold, and

Fig. 9 is a diagrammatic view of a modified form of gate, feeder and coating cavities.

In the drawings in which I have illustrated one form of mold embodying my invention and adapted for casting a thin walled, shallow article such as a frying pan, 95 1 indicates a mold base comprising a flat top 2 and suitable supporting legs or flanges 3. At the rear of base 1 a pivot pin 4 is secured to the base in an upright position. Two similarly formed complementary mold bodies 5 are pivoted to pin 4 by outstanding 100

lugs 6, the mold bodies 5 being slidably seated on the base and being adapted to swing about pin 4. 7 indicates another mold member removably secured to base 1 on the top surface thereof and in a position to engage and cooperate with one end of each of mold bodies 5 in certain positions of the latter. Suitable securing means for mold body 7 are indicated at 8, where bolts are shown passing through a flange portion 9 of body 7 but if desired bolt 8 may be omitted and the mold body left free to be moved on base 1. Suitable pilot or positioning means for determining the proper positions of the several mold bodies may take various forms but I have shown dowel pins 1^a mounted in the top of base 1 and engaging in recesses in the meeting faces of the mold bodies which have been found satisfactory.

20 In the meeting faces of mold bodies 5, recesses are suitably formed to constitute gate, feeder, casting and riser cavities when the bodies are in engagement with each other. These cavities are designated respectively by numerals 10, 11, 12 and 13 on Fig. 2. Preferably the inner face of mold body 7, or the surface thereof which is adjacent one end of mold bodies 5, is substantially vertical, although if it is desired to form a casting in a position other than substantially vertical as is here shown, this surface may be correspondingly inclined. The inner face 14 of mold body 7 forms the edge or end walls of the casting cavity 12, the remaining outer sides of the casting cavity being formed by the walls of the mold bodies 5. Mold body 7 carries a movable core 15 slidably mounted therein in a substantial horizontal position. This core is substantially circular in cross section, and is of sufficient length so that its inner end projects beyond the inner surface 14 of mold body 7 and into casting cavity 12 where the inner end and exposed side-walls of the core constitute walls for forming the interior of the casting cavity.

Core 15 is preferably hollow with its walls suitably proportioned in thickness to the size and nature of the casting desired. To facilitate movement of core 15 in mold body 7, as is desired for ready removal of the casting from the casting cavity, bracket 16 is secured to the mold body 7 by suitable means indicated generally at 17. This bracket is perforated, as at 18, to receive a screw threaded rod 19 engaging in a threaded hole 20 in cross bar 21 secured to core 15. Collars 19^a pinned to rod 19 on either side of bracket 16 prevent longitudinal movement of the rod through the bracket and when the rod is revolved, as by hand wheel 19^b, the rod serves to move core 15 relative to mold body 7. It will be obvious that other means may be used for actuating core 15 in mold body 7, but such means are considered mechanical equivalents of the form herein

illustrated and accordingly are not shown or described.

It will, of course, be obvious that the core 15 may be dispensed with in molds for certain types of castings, for example, flat or relatively shallow articles, or flanged articles having a flange extending away at an obtuse angle, in which case the mold body 7 may present a continuous surface 14 to mold bodies 5 instead of being cut away for a core as here shown.

22 designates a core pin adapted to seat on the top of the mold bodies 5 and 7 and to pass through an opening in the meeting faces thereof and projected into the casting cavity 80 for the purpose of forming a cored out opening in a handle lug 28 on the casting.

It will be understood that other forms of core pins may be used when occasion demands, and that the nature of the casting being made will to some extent determine the location of the pin with respect to the mold bodies. All such pins are however, considered to be the equivalent of the one herein shown.

Main core 15 has a substantially circular side surface adjacent the inner end thereof to form a substantially circular inner wall for the casting.

The new and improved form and arrangement of the casting and riser cavities contribute to the casting of articles requiring sound, non-porous smooth surfaced articles of the class described, with a minimum of grinding and other finishing operations being required. By reason of the gate and feeder cavity communicating with the casting cavity along the rear side thereof which corresponds to the bottom of the casting, it will be evident that the only finishing operation required will be a severing of the gate metal and the bottom of the casting and riser metal from the handle lug. The cost of the castings is thus greatly reduced.

For articles of the class shown where the article is cast in an upright position and the molten metal is led under the action of gravity through a considerable vertical distance, the improved form of gate and feeder cavities illustrated are preferable.

The gate indicated as an entirety at 10 comprises a downwardly extending inlet passage 10^a inclined slightly to the vertical which communicates at its lower end with a restricted passage 10^b which turns abruptly about point 20 and extends upward and rearward or away from the casting cavity to a point 21 above point 20, the passage thus serving as a means of retarding and more or less controlling the speed of flow of the entering molten metal as well as forming a liquid seal which tends to trap out light impurities and prevent their entry into the casting cavity. From point 21 passage 10^b curves downwardly and forwardly, or

toward the casting cavity, at a progressively increasing angle to the vertical and flares out adjacent to the feeder cavity in a vertically elongated, relatively narrow fan shaped discharge passage 10^c which preferably has a small width as compared with other parts of the gate 10 and an upright dimension approximately equal to the height of the feeder cavity 11.

10 The feeder cavity preferably extends upwardly to a point above the main portion of the casting cavity 12. Where projections from the main casting are to be cast above the main casting cavity, as handle stud 28 15 (Fig. 8), a riser cavity 13 may be provided to insure proper filling of the stud cavity.

Feeder cavity 11 is joined to casting cavity 12 by a short narrow passage 11^a which may be formed conveniently by projecting ribs 20 or ridges on the faces of the mold halves, as shown in Figs. 1 and 2.

Fig. 8 shows, in perspective, an article 25 with gate and riser attached as it appears when cast in a mold of the foregoing description. 24 indicates the casting proper which is a thin walled, shallow or pan-like article having a flat bottom 25, sides 26 provided at diametrically opposite points with out-turned lips 27, and a short handle 28. 30 35 29 indicates a quantity of metal forming a riser in communication with handle 28. 30 indicates a quantity of metal formed in feeder cavity 11 and connected to article 24 by a thin neck 31. A portion of the gate metal formed in gate 10 is indicated at 32.

In the operation of the mold illustrated, the mold bodies 5 are swung into assembled relation with mold bodies 7, and main core 15 and core pin 22 are brought to their 40 proper positions with respect to the mold bodies and casting cavity after the parts forming the cavities have been coated with a suitable mold coating composition. The mold bodies, and chiefly those in which the 45 gate and feeder cavities are formed, having first been brought to the desired operating temperature, as by applying a heating flame thereto or by other suitable means, a molten metal which may consist of aluminum or its 50 alloys or other light weight metals having relatively high crystallization shrinkage as compared with iron is poured into the inlet passage 10. It immediately fills the pocket or passage 10^b at the bottom of passage 10^a, thus effectually sealing the control passage 10^b and preventing light impurities on the 55 surface of the molten metal from entering passage 10^c. The metal with its velocity materially decreased flows upwardly through passage 10^b and passes downwardly and forwardly into the discharge passage 10^c at a velocity materially less than if it had fallen from the top of the mold bodies without interruption, and thence flows into feeder and casting cavity smoothly and without leap-

ing or sufficient velocity to cause harmful agitation, breaking up or splashing of the metal which may result in the entrapping of air therein and the consequent production of porous or pitted castings. As the pouring 70 proceeds, the molten metal enters the bottom of the casting cavity and rises in the casting and feeder cavities with the entering metal tending to flow outwardly across the top of the molten metal therein, which action is to 75 some extent continued, due to the curving upper surface of passage 10^c, until the feeder cavity 11 is completely filled. By providing an enlarged feeder cavity, a quantity of molten metal may be maintained in communication with the metal in the casting cavity until it has solidified to compensate for voids in the casting caused by shrinkage of the casting during solidification, the resulting casting being thus rendered substantially 80 85 free from crystallization shrinkage defects.

The first entering metal will presumably impinge against the part of the core directly opposite the opening 11^a but due in part to the configuration of the gate subsequently entering metal will flow onto the top of the molten metal already in the casting cavity, and successively strike against higher parts of the core thus avoiding the excessive heating of certain portions of the mold or core. 90 95 However, I have provided a boss 23 on the core adjacent the point of first contact of the molten metal therewith for the double purpose of rapidly dissipating heat from the face of the core in contact with the first entering molten metal and for providing a pad to which an insert could be attached should the outer face of the core become worn or corroded. In practice this boss has not been found necessary however. 100 105

Although the particular type of gate and feeder herein shown is particularly applicable to the type of casting illustrated, (it may be utilized to advantage with other types of casings not illustrated), it may be utilized to advantage with other types of castings wherein the vertical height of the casting cavity is relatively large. 110

Furthermore, it will be obvious to those skilled in the art that this improved form of gate and riser can be equally as well employed where the gate, feeder and casting cavities are in substantial alignment instead of being transversely positioned as shown herein. With such arrangement of cavities, 115 it is often possible to use only two movable mold bodies instead of three as here shown, and as an illustration of such molds reference is made to Patent 1,296,588 granted March 14, 1919, to J. H. Bamberg. 120 125

The arrangement of the gate and feeder cavities at substantially right angles to the medial part of the casting cavity is of especial importance where the casting has a thin section, since it is in accord with the prin- 130 135

5 ciple of causing the molten metal to flow a minimum distance thru narrow or shallow casting cavities. With the illustrated ar-
5 ange of cavities the molten metal flows each way laterally from the feeder cavity thus traveling the minimum distance thru the narrow cavity to reach all parts of the casting cavity. Somewhat similar results could be obtained by feeding metal into op-
10 posite edges of the casting cavity thus caus-
ing the metal to flow from opposite sides toward the medial portion of the casting cavity.

15 If desired the oppositely located feeder cavities may be supplied by a single gate outside the casting cavity as is indicated diagrammatically in Fig. 9 where 33 indicates a casting cavity, 34 the opposite feeder cavities, 35 the gate and 36 a passage con-
20 necting the two feeder cavities.

25 I do not wish to be understood as limiting my invention to the particular article shown but on the contrary contemplate the casting of many different sizes of types of articles, for culinary and other uses and including
pans of various depths, griddles, covers, plates and similar articles.

30 This application is a division of my co-pending application, Serial No. 641,359, filed on or about May 25, 1923.

35 Having thus described the invention in some sufficient detail to permit those skilled in the art to practice the same, what is de-
sired to be secured by Letters Patent is de-
25 fined by what is claimed.

What is claimed is:

1. A mold for casting articles of the class described provided with a casting cavity, an upright feeder cavity adjacent to the casting cavity, a short, narrow passage joining the said casting and feeder cavities throughout substantially the entire length of the casting cavity, and a gate for conducting molten metal into the said feeder cavity, the said gate comprising an inlet passage extending downwardly from the top of the mold, an upwardly and rearwardly and then downwardly extending passage communicating with the lower end thereof, and a vertically elongated discharge passage opening into the said feeder cavity.

2. A mold for casting articles of the class described, provided with a casting cavity, an upright feeder cavity adjacent to the said casting and feeder cavities throughout substantially the entire length of the casting cavity and a gate for conducting molten metal into the feeder cavity, the said gate comprising an inlet passage extending downwardly, an upwardly and rearwardly extending seal passage which turns downwardly and forwardly and a narrow, vertically, elongated discharge passage communicating with the said feeder cavity.

65 3. A mold for casting articles of the class

described, provided with a casting cavity, an upright feeder cavity adjacent to the said casting cavity, and communicating therewith through a short, narrow passage, and a gate for conducting molten metal into the 70 said feeder cavity, the said gate comprising a downwardly extending inlet passage a control passage, of restricted cross sectional area turning abruptly and laterally at the lower end away from the casting cavity and 75 extending downwardly and forwardly and terminating in a discharge passage flaring widely in a vertical plane and communicat-
ing with the said feeder cavity.

4. A mold for casting articles of the class 80 described provided with a vertically elongated casting cavity, an upright feeder cavity adjacent to the casting cavity, a short, narrow passage joining the said casting and feeder cavities throughout substantially the entire vertical length of the casting cavity, the said feeder cavity having larger cross sectional dimensions than either the short, narrow passage or the casting cavity, and a gate for conducting molten metal from the top of the mold into the said feeder cavity, the said gate comprising a downwardly extending inlet passage, an upwardly and rearwardly extending passage leading from the lower end thereof and constituting a liquid seal when molten metal is poured into the inlet passage, and a passage extending downwardly from the said upwardly extending passage and opening into the said feeder cavity throughout a relatively large portion of the vertical length of the said feeder cavity.

5. In a mold for casting metallic articles, the combination of a mold base and a plurality of mold bodies mounted thereon, the meeting faces of the said mold bodies being recessed to form gate, feeder and casting cavities, the said gate cavity being adapted to conduct molten metal under the force of gravity in a substantially unbroken mass to the feeder and casting cavities, comprising a downwardly extending passage of slight inclination to the vertical, an abruptly and rearwardly curved passage of constricted area, turning downwardly and forwardly and with increasing inclination to the vertical and a discharge passage enlarged in a vertical plane adjacent to and opening into the feeder cavity.

6. In a mold for casting metals having a high crystallization shrinkage as compared with iron into articles having a relatively thin wall portion, the combination of co-operating mold bodies having a casting cavity formed in the meeting faces thereof, a certain portion of the said casting cavity being relatively shallow for forming a thin wall portion of a casting, a vertical feeder cavity communicating with the casting cavity throughout a major portion of the ver- 130

tical height of the casting cavity, and a gate passage formed in the mold bodies to conduct molten metal to the feeder cavity, the said gate passage being flared vertically adjacent to the feeder cavity and communicating therewith throughout the major part of the vertical height of the feeder cavity, the said feeder cavity being so arranged with respect to the casting cavity that molten metal delivered thereby to the casting cavity flows a minimum distance through the shallow portion of the casting cavity with molten metal progressively entering the casting cavity on top of metal previously delivered to the casting cavity.

7. In a mold for casting aluminum or aluminum alloy articles having a thin wall portion the combination of cooperating mold bodies having their meeting faces recessed to form communicating gate, feeder and casting

cavities, the said casting cavity having a shallow portion for forming a thin wall portion of a casting, the feeder cavity communicating with the casting cavity throughout a major portion of the vertical height of the latter and so disposed with respect to the shallow portion of the casting cavity that molten metal in filling the casting cavity flows a minimum distance from the feeder cavity through the said shallow portions of the casting cavity, the said gate cavity communicating with the feeder cavity throughout a major portion of the vertical dimension of the latter and adapted to deliver heated metal progressively from the bottom to the top of the feeder cavity.

In testimony whereof I hereunto affix my signature this 12th day of March, 1925.

ALLEN B. NORTON.
